UNITED STATES PATENT OFFICE

JOHN M. WATSON, OF SHELL, WYOMING

AX

Application filed May 25, 1929. Serial No. 385,826.

This invention relates to improvements in axes and has reference more particularly to an ax provided with a removable bit portion or cutting blade.

Hunters, trappers and other people who spend a large amount of time in the woods camping and which are away from settled communities often find that they are handicapped due to the fact that their ax becomes dull and as they as a rule have no means for sharpening an ordinary ax, this often becomes a matter of serious importance.

It is the object of this invention to produce an ax which shall be so constructed that the bit portion thereof is formed from a removable blade that can be readily detached and replaced by another blade and which therefore makes it possible for anyone to carry a considerable number of blades and thus be able to provide himself with a sharp blade whenever this becomes necessary.

I am aware that axes with removable blades have been patented and I do not claim to be the inventor of this idea in its broadest aspect, but my invention is directed more particularly to a specific construction which makes it possible to employ removable blades of a very simple shape and form and which obviates the necessity of having specially constructed blades and this makes it possible for the owner of the ax to manufacture his own blades, if necessary, and for a manufacturer to make and sell the blades at a much smaller price than if the blades having special construction is employed.

Another object of this invention is to produce a handle which is made in several parts and which can be readily separated so as to convert the ax into a hand ax suitable for use with one hand, or into an ordinary ax suitable for use with both hands, as occasion may require.

The above and other objects which may appear as the description proceeds are attained by means of a construction and an arrangement of parts that will now be described in detail, reference for this purpose being had to the accompanying drawing in which the preferred embodiment thereof has been illustrated, and in which:

Fig. 1, is a side elevation of an ax constructed in accordance with my invention, portions thereof being broken away to better disclose the construction;

Fig. 2 is a section taken on line 2—2, Fig. 1; 55

Fig. 3 is a side elevation of the ax head showing the cutting blade removed; and

Fig. 4 is a perspective view of the blade.

In the drawing numeral 1 represents the ax head which is provided with an opening 2 for the reception of a handle 3. This opening or eye is located near the hammer end 4 of the ax head. The opening 2 is tapered inwardly to a point indicated by reference numeral 5 and is then tapered outwardly so as to form an opening having two tapered portions whose minimum cross section is at point 5. That portion of the handle which projects into the opening 2 is tapered to correspond with the taper of this opening and is provided with a threaded opening 6 for the reception of the bolt 7. This bolt extends through a plug 8 which fits into the other end of opening 2 and when the bolt 7 is tightened, the handle is clamped securely to the ax. The handle is made from steel and is hollow. As before intimated this handle is made in two parts, one of which has been indicated by reference numeral 9 and which is provided at one end with a tenon 10, which extends into the open end of the other member and the two parts are then secured to each other by means of bolt 11. When the ax is to be used as a hand ax, the part 9 is removed but can readily be connected with the part 3 when the ax is to be used with the two hands.

The ax head 1 is provided at one end with a rabbet 12, the side wall of which is provided with a number of studs 13 that are preferably formed integral with the ax head. The plane of the side wall of the rabbet is parallel with the longitudinal axial plane of the ax head and the end wall 14 preferably makes an obtuse angle with the side. The angle that the end wall makes with the side is slightly greater than ninety degrees, but the inclination does not need to be very large. This angle of inclination has been designated by W in Fig. 2. The blade 15 is provided with 100

a sharp cutting edge 16 and a plurality of openings 17. These openings are so located that they will receive the studs 13 when the blade is in place as shown in Fig. 2, and are of substantially the same diameter as these studs. The studs should fit these holes very closely but care should be taken that the plate can be removed without any special tools. The distance from the center of the opening 17 to the rear wall 18 of the cutting plate should be a trifle greater than the distance from the center of the studs to the nearest part of the end wall 14 so that the end 18 of the plate will fit closely against wall 14 when the plate is put in place. The plate 15 should be slightly thicker than the height of the lugs as shown in Fig. 2 so that the cover plate 19 will rest on the side of the plate 15 when the screws 20 are tightened, as by this means the plate 15 will be securely clamped against the side of the rabbet and will be rigidly held in position.

Owing to the fact that the cutting plate 15 can be made from a piece of sheet steel, no special tools are required for making this plate and therefore it can be very cheaply manufactured and it is even possible for a person provided with ordinary blacksmith tools, to construct a serviceable plate for this ax.

I want to call particular attention to the construction employing the lugs and the removable plate 19 as by this construction, it is possible to secure the blade 15 very rigidly to the head 1 and to simplify the construction of the blade as above pointed out.

Having described the invention what is claimed as new is:

An ax comprising a head having a socket 40 for a handle, the bit end of said head having a rabbet adapted to receive a removable blade, the side wall of the rabbet having a plurality of spaced studs adapted to project into openings in the removable blade, said 45 studs having axial threaded openings, a cover plate adapted to form a cover for the open side of the rabbet and screws extending through the removable plate and into the threaded openings in the studs for holding 50 the stud in place.

In testimony whereof I affix my signature.
JOHN M. WATSON.
